JACQUARD MACHINES

Frank Horsfield Haslam-Jones, West Bridgford, Nottingham, England, assignor to John Jardine Limited, New Basford, England

Application March 25, 1955, Serial No. 496,761

Claims priority, application Great Britain March 25, 1954

5 Claims. (Cl. 87—14)

This invention is for improvements in or relating to jacquard machines. A jacquard machine is a machine which provides individual control means for a plurality of operating members, and conveniently the operating members are biassed in one direction and the jacquard control means enables them to be moved against the biassing means in the opposite direction. A card having marks, for example apertures corresponding to each of the operating members to be controlled may be employed so that each time a selector controlling an individual operating member engages a mark on the card the member is operated. When the selector does not engage a mark that member is not operated.

This invention is concerned with jacquard machines in which springs are employed to bias the operating members.

It is an object of this invention to provide improvements in jacquard machines for use with textile machines and particular but by no means exclusive reference to jacquard machines for use with "go-through" or Levers lace machines. A Levers lace machine makes fabric by the wrapping of bobbin threads around a plurality of warp and beam threads and the fabric is patterned by the shogging one way or the other of the warp and beam threads between each bobbin thread. For this purpose the warp and beam threads are passed through holes or slots formed in steel bars (guide bars) which extend the length of the machine. The shogging of the warp and beam threads is obtained by the movement of these steel bars which is conveniently controlled by a jacquard machine. The jacquard mechanism for selecting and moving the steel bars is customarily located at one end of the lace machine and movement is imparted to the steel bars from the selecting mechanism by means of a steel strip and driving bars. At the other end of the machine the steel bars are anchored to coil springs to bias them against the movement of the driving bars.

It will be appreciated that in a lace machine there are many sets of warp and beam threads and consequently if each set of warp or beam threads is to be separately controlled there must be an equal number of steel bars and an equal number of springs biassing these steel bars. The steel bars themselves are in the order of $\frac{1}{1000}$ inch thick while the coils of the springs may be $\frac{5}{15}$ inch in diameter and consequently the space occupied by all the steel bars together is comparatively small compared to the space occupied by the springs. Hitherto it has been the practice to connect the steel bars to the springs by means of steel strip or a cord, the springs being located some distance from the lace machine and with their axes, i.e. the imaginary line upon which the spring extends, substantially horizontal. The axes of the steel bars are also horizontal. This results in the machine being of considerable length as it will be appreciated that the steel strips or cords from the steel bars to the springs are fanned out to accommodate the increased space which the springs necessarily occupy.

2

It is one object of the present invention to provide improvements in jacquard machines for use with lace machines of the kind referred to.

Accordingly the invention may be said to reside in the provision of a mounting for the biassing springs of a jacquard machine of the kind referred to wherein the springs provide a biassing force about an axis transverse to the direction of the required biassing force comprising means for anchoring the springs and means for transferring the biassing force from a vertical direction to a substantially horizontal direction. Preferably the springs are mounted about a substantially vertical axis. The springs may be located in a frame so as to be releasably secured therefrom for replacement as desired. Furthermore some of the steel bars may be employed to control warp or beam threads which are moved a greater distance than others or which are of thicker yarn than others. Accordingly it is desirable that there be provision for varying the tension applied to different steel bars according to the particular function or the nature of the yarn which that steel bar controls. Hitherto it has been found that operatives of jacquard machines have a tendency to increase the tension of the springs irrespective of the function which the steel bar tensioned by that spring has to perform. It will be readily appreciated that the adjustment of springs to the correct tension is highly skilled and in order that satisfactory operation of the lace machine shall be obtained it is desirable that only those possessing the necessary skill shall have access to the means for tensioning the springs.

According to a further feature of the present invention there is provided a mounting for the springs of a jacquard machine in which the tension of the springs may be adjusted, having a removable cover for the springs, a removable cover for the means for adjusting the tension of the springs, and a single lock for both said covers. Conveniently the mounting comprises a frame in which the springs are located with their axes substantially vertical and having means for transmitting the force exerted by the springs in a vertical direction to a substantially horizontal direction to the steel bars; such means may conveniently comprise an axle and pulley for each individual cord, wire or the like connecting a spring to a steel bar. Conveniently the means for adjusting the tension of the springs comprises an anchor member attached to the end of the spring and extending through an aperture in the form of a slot, said member and slot having co-operating means for adjusting the length of said member extending through the slot which means may for example be a plurality of lateral extensions provided on the outer member. In one construction the springs may be housed in one part of the container and the said anchor members extending through slots in that container into another container. The extension serves to prevent the members passing through the slots except when said members are twisted to bring the slots and extensions into register. In such a construction it is desirable that there be provided ready access to both containers, for example by removable covers to both said containers and this invention provides a single lock for both said covers and co-operating means so that removal of one cover permits removal of the other cover.

More specifically the invention provides a mounting for the biassing of springs of a jacquard machine wherein the springs provide a biassing force in a substantially vertical direction comprising at least one rotatable member for each of the springs in the mounting located at one end of the mounting for transferring the vertical biassing force into a horizontal biassing force, at least one aperture for each of the springs in the mounting, at the other end of the mounting a removable cover for that part of the mounting between the rotatable member

and the aperture, a hinged cover for that part of the mounting beyond the aperture and interconnecting means between the covers so that the removable cover may only be removed when the hinged cover is hinged open to expose said aperture.

This invention further provides, in a lace machine having guide bars or "steel" bars controlled by a jacquard machine and tensioned by tension springs, an arrangement in which the axes of the springs are disposed transverse to the length of the bars and the springs are connected to the guide bars by flexible connections which are diverted, through the appropriate angle, by pulleys or the like.

In order that the invention may be more readily understood reference will now be made to the accompanying drawings which illustrated by way of example a specific embodiment of the invention:

Figure 1 is a side sectional view of a jacquard spring box according to this invention.

Figure 2 is a part sectional view of a front elevation of a jacquard spring box according to the invention.

Figure 3 is a plan view of Figure 2 with the top cover removed.

Figure 4 is a perspective view of a Levers lace machine and a jacquard machine.

A substantially rectangular hollow container 1 has an aperture 28 formed in the rear face thereof and is provided with a cover 2 in the front thereof. A bottom cover plate 16 is conveniently secured to the lower end of the frame 1 by suitable means such as for example by bolts (not shown). The plate 16 has a plurality of apertures in the form of slots 15 formed therein and has hinged to it a cover member 10 by means of the hinge pin 24. The cover 10 is positively located when in the closed position by the peripheral step 11 formed on the plate 16 and engaging a corresponding peripheral groove in the cover. As illustrated with respect to a Levers lace machine, the steel bars thereof 23 are connected by wires 22, to coil springs 17 anchored at their other end to anchor members 13 extending through the slots 15 in the plate 16 and having a plurality of steps 14 formed thereon. The wires 22 pass over individual pulleys 19 mounted for rotation upon shafts 18 housed in bearings formed in the container 1. A removable cover 20 for the top of the container has a knob 21 for easy removal thereof. A strut 8 extends across the open front of the casing 1 and has a rib extending rearwardly therefrom in which rib is formed a hole 9. The front cover 2 has a projection 5 integral therewith with a hole 29 formed therein. A pin 7 is mounted to extend through both the holes 29 and 9 and to extend through a hole formed in the bottom plate 16 and to abut a step 12 provided at one side of the cover member 10. A screw threaded member 4 co-operating with the screw thread formed in a hole in the front casing 2 is provided with a knob 3 for rotation and mounted to contact the strut 8. The cover member 10 is provided with a lock 25 operated for example by a key 26. In operation the steel bars 23 are tensioned by the springs 17 which are anchored by the anchor members 13 each having a series of lateral extensions 14 for engaging the lower surface of the plate 16. To alter the tension of a given spring the anchor member is eased so that the extension does not abut the bottom surface of the said plate 16 and then twisted so as to permit the member to slide through its slot to a new position. The anchor member is then twisted back to its original attitude and the appropriate extension engaged with the plate 16. The extensions 14 may be arranged at intervals of height in each member 13 such that between each extension a difference in tension of half a pound on the spring may be obtained.

The cover plate 2 is locked in position by the pin 7 extending through holes 9 and 29 and thereby preventing the removal of the cover 2. Positive location of the

cover 2 is obtained by screwing the member 4 against the struts. The pin 7 is held in position by the step 12 and it will be appreciated that this step is only able to hold the pin 7 wholly within the hole 29 when the cover member 10 is located in the closed position. By unlocking the lock 25 the cover member 10 may be swung down into an open position thus revealing the tension members 13 for convenient adjustment thereof if desired and in so doing the pin 7 drops vertically as the step 12 is removed and dis-engages from the hole 29 thus releasing the cover 2. A collar 30 on the pin 7 may be provided to prevent the pin passing through the hole 9.

In Figure 4 a jacquard machine is housed within a casing 31, the punched cards of the jacquard machine and the selecting mechanism comprising droppers or the like and means for progressing the cards one at a time and placing them against the selecting mechanism is contained within this housing. The selecting mechanism individually controls the steel bars 23 which are fanned out and which enter the lace machine and pass through the centre of the machine; each of the steel bars having one or more apertures for the passage of a warp thread. A motor 35 provides the power for the lace machine and take-up mechanism for the fabric 33 is driven through gearing 34. Warp beams are located upon a warp beam rack 32. At the end of the machine remote from the housing 31 is the biassing spring mounting 1 as illustrated in greater detail in Figures 1 to 3.

It will be appreciated that a spring mounting according to this invention may be located at the end of a textile machine, for example Levers lace machine, remote from the jacquard mechanism and a considerable reduction in space at that end of the machine is obtained by mounting the springs in tension about a substantially vertical axis. It will also be appreciated that by this invention there is provided a spring mounting the covers of which may be readily removed for adjustment or replacement of the springs as desired.

Especially in adapting the present invention to existing lace machines it may be preferable to provide two initially separate castings, one for containing the pulleys and the other for providing the spring anchorages, bolted or otherwise fastened to an end standard of the machine, together with a box-like cover which is removably fitted over the two castings to enclose the whole assembly and is locked in position. This cover, which is removable to give access to the springs may be fabricated from sheet metal.

What I claim is:

1. In a jacquard machine of the type referred to the combination with operating members of flexible elements connected to the operating members, tension springs connected to the flexible elements, a stationary mounting, rows of guide members on the mounting guiding the flexible elements, and anchoring means for the springs comprising an anchorage on the mounting having slots, one for each guide member, and the slots being staggered in twice as many rows as the rows of guide members, and strip members which extend through the slots and are attached to the springs at the guide member side of the anchorage and also have projection means thereon at the other side of the anchorage preventing the springs pulling the strip members through the slots, whereby close positioning of the guide members and of the slots enables disposition of the springs in comparatively small block formation.

2. In a jacquard machine of the type referred to the combination with operating members of flexible elements connected to the operating members, tension springs connected to the flexible elements, a stationary mounting, rows of guide rollers on the mounting around which the flexible elements extend to be disposed angularly, and anchoring means for the springs comprising an anchorage on the mounting having slots, one for each guide member, and the slots being staggered in

twice as many rows as the rows of guide members, and strip members which extend through the slots and are attached to the springs at the guide member side of the anchorage and also have projection means thereon at the other side of the anchorage preventing the springs pulling the strip members through the slots, whereby close positioning of the guide members and of the slots enables disposition of the springs in comparatively small block formation.

3. In a jacquard machine of the type referred to the combination with operating members of flexible elements connected to the operating members, tension springs connected to the flexible elements, a stationary mounting, guide members on the mounting around which the flexible elements extend to be disposed angularly, and adjustable anchoring means for the springs comprising an anchorage fixed on the mounting and having slots, one for each guide member, and anchoring strip members which extend through the slots and are attached to the springs at the guide member side of the anchorage and also have lateral projections spaced longitudinally thereof, the overall width of the strips and the projections being slightly less than the length of the slots, whereby the anchorage strip members are turnable to align the projections and slots and are then bodily displaceable about their axes to adjust the tension of the springs and further turnable to mis-align the projections with the slots and maintain the tension by the appropriate projections abutting behind the anchorage.

10

15

20

30

4. In a textile machine having jacquard mechanism including horizontally movable thread guide members connected by flexible elements to biasing springs which are adjustable by adjustable anchoring members connecting tail ends of the springs to an anchorage, mounting means for the biasing springs and anchorage members to be disposed in vertical close group formation, comprising a support structure, and supported thereby, a close group of deflecting members for the flexible elements and an anchorage part, a close group of slots in the anchorage part, and blade-like elements, constituting the anchorage members, extending through these slots and having a plurality of oppositely directed lateral projections to allow for adjustments by turning movements of the blade-like elements.

5. Mounting means as claimed in claim 4 having the slots and consequently a blade-like element in close staggered relationship to enhance the close group formation of the springs.
